(57) **CLAIM**

The ornamental design for a computer casing as shown and described.

DESCRIPTION

The patent or application file contains at least one drawing executed in color. Copies of this patent or patent application publication with color drawing(s) will be provided by the Office upon request and payment of the necessary fee.

1.1 is a front perspective view of a computer casing;

1.2 is a top view thereof;

1.3 is a front view thereof;

1.4 is a right view thereof;

1.5 is a left view thereof;

1.6 is a back view thereof; and

1.7 is a bottom view thereof.

The broken lines in the Figures show portions of the computer casing which form no part of the claimed design. The color shown on the claimed design of the computer casing forms a part for the claimed design of the computer casing.
